FIG. 1

FIG. 2

FIG. 3

INVENTOR

BY JAMES A. SPEER
B. F. Frank ATTORNEY

UNITED STATES PATENT OFFICE

JAMES A. SPEER, OF WICHITA, KANSAS

PISTON

Application filed January 31, 1931. Serial No. 512,512.

This invention relates to improvements in an internal combustion engine and particularly to means for cooling the piston, and means for utilizing the piston for cooling the oil in the crank case of the engine. This is a particular advantage in air cooled engines.

By maintaining the inner end of the piston relatively cool and passing the air current of the fuel charge through the piston, the relatively cool charge can be compressed to a higher degree than is possible in an ordinary engine construction, since it is well recognized that the higher the compression of the fuel charge, prior to combustion, the more efficient the engine will be. It is obvious that my invention has certain advantages over engines of the ordinary type.

The novelty of my invention will be apparent by referring to the following description in connection with the accompanying drawing in which:

Fig. 1 is a view of a cylinder of a motor, part of which is in elevation and part in section, the piston being shown in section except for the connecting rod.

Fig. 2 is a cross sectional view through the piston at right angles to the section shown in Fig. 1.

Fig. 3 is a perspective view of part of the piston, parts being broken away to show the cooling fins and the fuel passageway there thru.

Referring now to the drawing by numerals of reference:

35 1 designates a cylinder of an internal combustion engine of the air cooled type, having an intake conduit communicating with the carburetor not shown, connected to a pipe 3 secured to the outlet 4 of a passageway 5 in the piston 6, the passageway having an inlet 7 adapted to intermittently register with an inlet opening 8 in the cylinder.

The engine is equipped with the usual intake valve 9 and with an exhaust valve not shown, as well as with a spark plug 10, of usual construction. The circumferential flanges 11 on the cylinder are for air cooling the cylinder. The piston 6 is provided with the usual skirt 12 and it is provided with 50 bearings 13 and 14 for the connecting rod

15. The head or inner end 16 of the piston cooperates with an inverted V shaped partition 17 to provide the passageway 5. The passageway 5 having its inlet 7 and outlet 4' as shown in Fig. 1.

Connecting the partitional web 17 with the head 16 are a plurality of vertically positioned partitions 18 in spaced relation, to divide the passageway 5 into a plurality of sub-passageways as shown, and immediately below the partitions 18 and carried by the inverted V shaped web 17 are similar oil cooling webs 19 which project into the skirt of the piston toward the wrist pin of the connecting rod.

On the suction stroke of the piston, fuel is drawn through the carburetor into the engine, but the air supply is drawn through the opening 8, through opening 7, through the sub-passageways, through opening 4', through opening 4, through pipe 3, through the carburetor and hence to the intake pipe or manifold 2. The cool outside atmosphere will take up some of the heat from the partitions or fins 18 before it enters the carburetor to commingle with the hydrocarbon content of the fuel mixture, so that the piston will be kept relatively cool. As the piston reciprocates, the oil in the crank case will splash on the fins or web 19, and since they are integral with the V shaped partition or web 17 and in line with the webs 18, they will remain relatively cool, thereby keeping the oil cool.

The V shaped web or partition 17 will slightly choke the passageway of the air through the piston to give it sufficient time to dissipate a considerable amount of heat from the piston. The webs and partitions in the piston, as well as the head and skirt, can all be cast integral, so that the piston may be constructed at a very low cost. Of course, appropriate sealing rings 20 will be provided for the piston at appropriate places.

Inasmuch as the incoming air passes through the piston and cools it, it will take up some of the heat, this heat being useful in vaporizing the liquid fuel in the carburetor. The mixture will not be so hot however, as to

interfere with high compression in the engine.

Attention is called to the fact that as the piston registers with the inlet opening 8, a 5 fresh charge of cool air is drawn into the passageway 5. As the piston ports lap the inlet and outlet ports in the cylinder, this cool air is trapped in the passageway, which now becomes a cooling chamber in the piston to 10 maintain the piston at a low temperature during all four strokes of the piston. This will prevent the piston from becoming excessively hot, and as heretofore pointed out, the heat taken up by the air will tend to en- 15 hance the vaporization of the liquid content of the fuel mixture as this relatively warm air passes through the carburetor. Where any forced feed oil system is employed the oil of course will be pumped through the 20 parts to be lubricated under pressure in the usual way, and this positive feed of the oil will cause the oil to contact with the oil cooling fins so that new oil will constantly flow over the oil cooling fins and thereby have 25 its temperature maintained relatively low.

Of course it is understood that the engine is susceptible for use with a super- 30 charger, in which event the supercharged air would be forced under pressure into the inlet 7, instead of depending upon the suction stroke of the piston for drawing the air through the carburetor.

What I claim and desire to secure by Letters Patent is:—

35. 1. A piston comprising a head having a cylindrical skirt provided with aligning openings, an inverted V shaped web spaced from the head to provide a passageway between the openings, and oil cooling fins on the outer 40 face of the web.

2. A piston comprising a head having a cylindrical skirt with aligning openings, a web spaced from the head to provide a passageway between the openings, heat conducting 45 webs connecting the first named web and the head, and fins connected to the outer face of the web.

3. A piston comprising a head having a cylindrical skirt provided with aligning openings, an inverted V-shaped web spaced from the head to provide a passageway between the openings, air-cooling fins connecting the web and head to divide the passageway into a plurality of ducts and oil cooling fins on 55 the face of the web opposite to the first named fins.

In testimony whereof I affix my signature.
JAMES A. SPEER.
